UNITED STATES PATENT OFFICE.

CYRUS CHAMBERS, JR., OF PHILADELPHIA, PENNSYLVANIA.

CUT-OFF-REGULATING DEVICE FOR BRICK-MACHINES.

SPECIFICATION forming part of Letters Patent No. 297,674, dated April 29, 1884.

Application filed December 26, 1883. (No model.)

To all whom it may concern:

Be it known that I, CYRUS CHAMBERS, Jr., a citizen of the United States, residing at the city and county of Philadelphia, and State of Pennsylvania, have invented certain new and useful Improvements in Cut-off Regulating Devices for Brick-Machines, of which the following is a full, clear, and exact description, reference being had to the accompanying drawings.

This invention is an improvement in the nature of a modification of the friction devices whereby the speed of rotation of the spiral cut-off blade of the Chambers brick-machine, as described in my Letters Patent No. 207,343, of August 27, 1878, and No. 275,467, of April 10, 1883, is caused to be accelerated automatically when the bar of clay issues from the die of the machine at a greater speed relatively than that of the cut-off blade.

In describing the present invention reference will be made more especially to the last-mentioned Letters Patent.

Figure 1 of the annexed drawings is an end elevation of the invention, looking toward the front or die end of the brick-machine. Fig. 2 is a side elevation, and Fig. 3 is a similar side view showing the position of the friction devices relatively to the cut-off blade. The latter figure corresponds with Fig. 18 of the Patent No. 275,467, the present belt-friction devices being substituted for the cone-clutch and gearing of that figure.

As described upon pages 4 and 5 of the patent last mentioned, the forward end of the shaft X, which carries the cut-off blade Q, (indicated by the broken lines,) runs in a box, Y, with a universal joint upon the top of a column, Z, which projects from a hollow standard, K', supported by a transverse rock-shaft, A'. The rear end of shaft X runs in a box, C', with a ball-and-socket joint upon the end of an upright lever, D', to which box C' is adjustably secured, and which upright lever is supported by a rock-shaft, B', on the main frame of the machine. B' carries a short lever or arm, D'', that engages with a washer, D'', bearing against the end plate of the female part of a cone-clutch, which is loose upon the main shaft W of the machine, and by its movement (arm D'')

increases or permits a diminution of the friction of the clutch-cones, &c.

In the present modification I make no change in the parts above referred to, save that I substitute in lieu of the cone-clutch the combination of devices which I shall now proceed to describe.

Upon the main driving-shaft W, I secure a flanged broad-faced pulley, K², and on the shaft I', whose gear K⁵ has the oblique and tapering cogs described in my Patent No. 275,467, meshing with the teeth of gear M³ on the shaft X, which carries the cut-off blade Q, I secure a small pulley, J², similar to K².

At the end of the upper arm or limb of a yoke, Y', which yoke is pivoted on the shaft W, is journaled an idler-roller, B, in line with the pulleys K² and J², whereby the inward movement of yoke Y' forces the idler against a broad belt, V, which passes around both of said pulleys, as indicated by the broken lines in Fig. 1. The movement of the yoke outwardly releases the pressure of the idler against the belt. The degree of friction, therefore, of the latter against the faces of pulleys K² and J² is governed by the throw of the vibrating yoke Y', and the consequent pressure or release of the idler in connection with the belt. The changes in the movement of the yoke upon its pivot that are necessary to be made in order to regulate the speed of the cut-off blade Q, Fig. 3, are induced in the manner previously alluded to, the lower arm of yoke Y' being provided with an adjustable set-screw, (or screws,) s, whose end extends into the path of lever D''. It is obvious that when the latter is rotated forward—that is, depressed by reason of the push of the bar of clay against the cut-off blade, as described in my said Patent No. 275,467—its lower side, bearing upon the end of the set-screw connected to the yoke-arm, depresses the latter and thus causes the idler B to bear with greater or less pressure against the belt V, as seen in Fig. 1. The arm D'' might be allowed to bear directly upon the top of the lower limb of the yoke; but it is preferred to make use of the set-screws s, as admitting of nice adjustments. As the belt hugs the pulleys K² and J² more closely, the force or speed carried by the belt from the

driving-shaft W causes the acceleration of the shaft of the cut-off blade. This friction-belt device, with the connections described, constitutes a "compensatory expedient," whereby the speed of the cut-off blade is regulated according to that of the bar of clay issuing from the die of the machine, which is practically as sensitive as that shown and set forth in my aforesaid Patent No. 275,467, for which device it may be substituted.

The weighted hand-lever J' is applied in the same manner, and is adapted to perform the identical function as described in my said patent; and, as it forms no part of the present invention, it is unnecessary to describe the same.

Having thus described my improvement, I claim—

1. The combination of the cut-off-blade shaft having gear M², the gear K², pulleys K² and J², the pivoted yoke having the idler B, and set-screws s, (or their equivalent,) the arm D² on rock-shaft B', and the lever D', con-

necting said cut-off-blade shaft and rock-shaft, all constructed and adapted to operate substantially as and for the purpose recited.

25

2. In a brick-machine of the recited class, the combination, with the cut-off mechanism, of an adjustable friction-belt device, substantially as shown and described, whereby, through suitable intermediate mechanism, the movement of the bar of clay issuing from the die of the machine is caused to operate said friction-belt device, and thereby causes the same to convey power to and to speed the cut-off mechanism correspondingly to the speed 35 of the bar of clay, substantially as set forth.

In testimony whereof I have hereunto affixed my signature this 18th day of December, A. D. 1883.

CYRUS CHAMBERS, JR.
